UNITED STATES PATENT OFFICE

165,661

GOLF CART HANDLE ARTICLE SUPPORT

Dale R. Morris, Walla Walla, Wash.

Application November 24, 1950, Serial No. 13,112

Term of patent 14 years

(Cl. D34—5)

To all whom it may concern:

Be it known that I, Dale R. Morris, a citizen of the United States, residing at Walla Walla, in the county of Walla Walla and State of Washington, have invented a new, original, and ornamental Design for a Golf Cart Handle Article Support, of which the following is a specification, reference being had to the accompanying drawings, forming a part thereof.

Figure 1 is a side elevational view of a golf cart handle article support, showing my new design;

Figure 2 is a top plan view;

Figure 3 is a front elevational view;

Figure 4 is an end view;

Figure 5 is a sectional view taken along the line 5—5 of Figure 3.

I claim:

The ornamental design for a golf cart handle article support, as shown.

DALE R. MORRIS.
